UNITED STATES PATENT OFFICE.

THOMAS N. RUDGERS, OF FOWLER, MICHIGAN.

NECK-YOKE.

SPECIFICATION forming part of Letters Patent No. 231,619, dated August 24, 1880.

Application filed April 12, 1880. (No model.)

To all whom it may concern:

Be it known that I, THOMAS NORTON RUDGERS, of Fowler, in the county of Clinton and State of Michigan, have invented a new and Improved Neck-Yoke; and I do hereby declare that the following is a full, clear, and exact description of the same, reference being had to the accompanying drawings, forming part of this specification, in which—

10 Figure 1 is a side view, and Fig. 2 a cross-section through line $\alpha\alpha$ of Fig. 1.

My invention relates to an improved construction of neck-yoke for connection with the end of the tongue or pole in a double team; 15 and it consists in the peculiar means for increasing or diminishing the leverage of the neck-yoke, or adapting it to unequally-matched horses.

In the drawings, A represents the neck-yoke, upon each end of which is fastened an elongated thimble, B, having upon the front side a set of lugs, a , with alternating notches. In any one of these notches, at each end, rest the rings b , that connect with the neck-gear 25 of the harness, and which rings are kept in place or prevented from slipping off the neck-yoke by a spring-guard, c , which incloses all of the notches. This spring-guard is set parallel with the ends of the neck-yoke, and is 30 sufficiently close to the ends of the lugs to prevent the ring from accidentally leaving the notch in which it may be placed, but, being made yielding or in the nature of a spring, may be forced out at will a short distance, to 35 allow the ring to be slipped from one notch to the other in changing its adjustment.

The merit of this arrangement is that it permits the horses to be adjusted closer together or farther apart, according to the requirements of use or peculiarity of the animals, and if one 40 horse be larger than the other one ring may be adjusted closer to the pole to distribute the leverage thereupon caused by the weight of the pole to suit the capacities of the two horses. This arrangement is also advantageous to 45 lighten the load on one of the horses if one should have a sore neck.

For connecting the yoke to the pole a tube, C, is made to embrace the middle portion of the yoke, and is formed of two semi-cylindrical pieces of malleable iron having flanges d , which are bolted or riveted together. In 50 perforated lugs e , near the ends of this tube, and in the flanged portion of the same, are arranged small rings or links f , each connecting with a larger ring, D, which is slipped over the pole. Now, when the back strain is on the neck-yoke the double connection of the rings f with the tube serves to hold the yoke 55 stiffly in a horizontal position, and does not allow it to sway backward and forward and hit the horses' legs.

Having thus described my invention, what I claim as new is—

A neck-yoke having at its ends a set of lugs, 65 a , and alternating notches, combined with a ring, b , and inclosing spring-guard c , substantially as and for the purpose described.

THOMAS NORTON RUDGERS.
